CABLE ARMOR CUTTER

Zoltan O. St. Palley, Branford, Conn.

Application June 25, 1952, Serial No. 295,525

10 Claims. (Cl. 29—67)

1

This invention, which is a continuation in part of my prior application, Serial Number 106,792 filed on July 26, 1949, and now abandoned, relates to an improved means for the cutting of the armor of cables formed of spirally wound strips. It is particularly applicable to electrical cables, known as BX cables.

In the installation of these cables the customary way is to cut the armor diagonally by means of a hack-saw. Due to the curvature of the surface of the cable, in such a diagonal cut the penetration of a straight hack-saw is the deepest in the center of the cut, decreasing gradually to zero toward the ends of the cut. Hence, if we limit the maximum penetration to the inside surface of the armor, the cut in the armor strip will be incomplete. Conversely, if we attempt to cut the armor strip completely by a straight hack-saw, the maximum penetration of the saw in the center of the cut will be so deep that the insulation of the wires may be damaged, causing a dangerous hazard in the electrical installation.

The object of my invention is to preclude the damaging of the insulation when cutting the BX armor, by providing a cutting means which can cut the armor strip in a line practically parallel to the axis of the cable, and thereby, can sever the armor strip completely without penetrating at any point deep enough to come in contact with the insulation.

Another object of my invention is to provide a rotary cutting means which is easily replaceable and is inexpensive, hence, a very high cutting efficiency can be maintained with very little effort and at a low cost.

Another object of my invention is to provide a tool for the cutting of the BX armor, in which the cutting means is withdrawn during the clamping of the cable in order to protect the cutting means from impact and from being applied with the wrong direction of rotation.

Another object of my invention is to provide a cutting tool for BX armor, in which the same crank serves for the tightening of the clamping means and also for the rotating of the cutting means, resulting in great ease and convenience in the handling of the tool.

A further object of my invention is to provide a tool which cuts the BX armor always the right way, entirely independently of the skill and attention of the operator and without de-forming the BX armor, and without the possibility of causing bodily injury to the operator, which is a too frequent occurrence when cutting BX armor by a hack-saw.

2

Other objects and advantages of the invention will be apparent during the course of the following description.

5 In the accompanying drawing, forming a part of this application, wherein, for the purpose of illustration, is shown a preferred embodiment of my invention.

Figure 1 is a plan view of my cable armor cutter.

10 Figure 2 is a vertical longitudinal section through the same, with the crank in the cutting position.

Figure 3 is a front view of the cutting means, Figure 4 is a vertical longitudinal section of my cable armor cutter, with the crank in the clamping position.

Figure 5 is a side view of the cable, showing the completed cut.

Referring to the drawing, wherein like reference numerals are employed to designate like parts, the numeral 2 designates a cup-shaped clamp, having a cavity for receiving an armored cable 1. Rib-shaped portion 3 of said cavity projects into the spiral groove of the armored cable 1, for positioning the cable axially.

Tubular clamping screw 4 is in threaded relation with clamp 2, so that by turning the clamping screw 4 cable 1 can be held securely in clamp 2. Clamping screw 4 has notches 5 at its free end.

30 Rotatably and slidably mounted within the clamping screw 4 is plunger 6, which at one end carries the cutting means 7, consisting of a holesaw or hollow-drill, secured by means of split washer 9 and retaining screw 10.

35 Plunger 6 is surrounded by spring 8, interposed between the shoulder of the plunger and the inverted flange of the clamping screw 4, so as to press the cutting means 7 against the cable 1.

40 Pivots connected to plunger 6 is a crank 11, having a handle 12 and a lug 13. Said pivotal connection permits the crank 11 to be swung up from the cutting position, shown in Fig. 2 of the drawing, into the clamping position, shown in Fig. 4. In the cutting position crank 11 is used for rotating plunger 6 together with the cutting means 7, heretofore called hole-saw or hollow-drill. In the cutting position crank 11 may be used also to exert manually in axial pressure on the plunger to supplement the pressure of the spring 8. In the clamping position crank 11 engages the clamping screw 4 by means of lug 13 projecting into notch 5, so that the clamping screw can be rotated by means of 45 50 55 crank 11.

The pivotal end of crank 11 is bifurcated and has an eccentric outline with respect to pin 14, giving a cam effect, so that when crank 11 is swung up into the clamping position (see Fig. 4) plunger 6 together with the cutting means 7, are withdrawn out of contact with the cable, in order to prevent damage to the teeth during the clamping.

Fig. 3 of the drawing shows a front view of the cutting means 7 which, in this preferred form, consists of a short saw blade bent in a circle and with the ends of the blade not attached. It will be within the spirit and scope of this invention to use closed annular, cylindrical, conical, cup-shaped or any other type of holesaws or hollow-drills, made of any suitable material, provided they can penetrate the armor of the cable when subjected to rotation and simultaneous axial pressure.

Fig. 5 of the drawing shows a side view of the cable 1 with the completed cut. The dotted circles indicate the relative position of the cutting means 7 with respect to the cable. The numeral 15 designates the point of the armor strip in the cut which is the nearest to the center line of the cable. It is an essential feature of my invention that the cutting means 7 is located tangentially to a plane passing through the center line of the cable 1, giving a cut which severs the armor strip completely, without penetrating at any point deep enough to come in contact with the insulation within the armor.

As shown in Fig. 2 of the drawing, cutting means 7 is recessed in the plunger 6, so that the maximum penetration is limited by the projection of the cutting means 7 beyond the end of the plunger 6. In my invention this projection of cutting means 7 is just sufficient to reach the innermost point 15 of the armor strip, but will not reach the insulation within the armor of the cable.

The method of operation will be as follows:

Crank 11 is moved into the clamping position, cable 1 is inserted into the cavity of clamp 2 and clamping screw 4 is turned by means of crank 11 until the cable is firmly clamped.

Then, the crank 11 is swung into the cutting position and is rotated by means of handle 12. After a few turns the cut in the armor is completed, which is noticed by the ease of turning the crank.

Then, the crank 11 is swung back into the clamping position and the cable is unclamped. In this position the tool is ready to receive the next cable for cutting.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

I claim:

1. A clamp adapted to hold and axially position a BX cable; a hollow clamping screw, directed toward the side of said cable and having threaded relation with said clamp; a plunger rotatably and slidably mounted within said clamping screw; a hole-saw secured to one end of said plunger; a spring to press said hole-saw against said cable; a crank for the manual rotation of said plunger, having a pivotal connection with said plunger, said crank being adapted to withdraw said hole-saw from contact with said cable and to engage said clamping screw for

the purpose of rotation, when said crank is swung about said pivotal connection.

2. A clamp adapted to hold and axially position an armored cable; a hollow clamping screw, directed toward the side of said cable and having threaded relation with said clamp; a spring pressed plunger rotatably and slidably mounted within said clamping screw; a hole-saw secured to one end of said plunger; a crank having two positions: cutting and clamping positions; connecting means adapted to rotate said plunger by turning said crank; means for withdrawing said hole-saw from contact with said cable when said crank is moved into the clamping position; means for obtaining driving engagement between said crank and clamping screw when said crank is in the clamping position.

3. A clamp adapted to hold and axially position a BX cable; a tubular clamping screw in threaded relation with said clamp; a spring pressed hollow-drill rotatably and axially slidably mounted within said clamping screw; a crank, adapted to selectively rotate either both of said clamping screw and said hollow-drill, or only said hollow-drill; means for withdrawing said hollow-drill from contact with said cable before rotating said clamping screw.

4. A clamp adapted to hold and axially position a BX cable; a tubular clamping screw in threaded relation with said clamp; a spring pressed hollow-drill rotatably and slidably mounted within said clamping screw; a crank having two positions: cutting and clamping positions; connecting means adapted to rotate said hollow-drill by turning said crank, when said crank is in the cutting position; connecting means adapted to rotate said clamping screw by turning said crank, when said crank is in the clamping position.

5. Clamping means adapted to hold and axially position an armored cable; spring pressed hollow-drill, directed to the side of said armored cable and being rotatably and axially slidably mounted in said clamping means; a crank, having two positions and being adapted to rotate said hollow-drill when said crank is in the first position and to withdraw said hollow-drill from contact with the cable when said crank is moved into the second position.

6. In a tool for cutting the armor strip of a BX cable; a clamp adapted to hold a BX cable; a positioning rib secured to said clamp and projecting into the spiral groove of said cable, for the axial positioning of said cable; a tubular clamping screw in threaded relation with said clamp; a spring pressed plunger rotatably and slidably mounted within said clamping screw; a hole-saw secured to one end of said plunger, said hole-saw being tangential to a plane passing through the center line of said cable and said hole-saw being recessed into the end of said plunger so as to limit the maximum penetration of the hole-saw to the thickness of the armor strip.

7. In a tool for cutting the armor strip of a BX cable; clamping means having a cavity with rib projecting into the spiral groove of said cable, for axially positioning and securely holding said cable; a rotatable and axially slideable hollow-drill mounted tangentially to a plane passing through the axis of said cable; a spring for pressing said hollow-drill against said cable; a crank for the manual rotation of said hollow drill, said crank being adapted to transmit an axial manual pressure to said hollow-drill in order to sup-

plement the spring pressure for the purpose of controlling the speed of the cutting.

8. In a tool for cutting the armor strip of a BX cable; clamping means for holding said cable; a plunger directed toward the side of said cable and rotatably and axially slidably mounted in said clamping means; a hole-saw recessed into one end of said plunger so as to prevent its penetration beyond the innermost point of said armor strip; positioning means, integral with said clamping means, to position axially said armor strip with respect to said hole-saw; a spring for pressing said hole-saw against said cable; means for the manual rotation of said hole-saw.

9. In a tool for cutting the armor strip of a BX cable; a clamp adapted to hold said cable; a tubular clamping screw, in threaded relation with said clamp, directed toward the side of said cable; a hollow-drill, rotatably and slidably mounted within said clamping screw with an axial clearance, which permits the turning of said screw until said cable is securely clamped, without pressing said hollow-drill against said cable; manual means adapted to rotate said hollow-drill and also to transmit simultaneously an axial pressure on said hollow-drill, by the use of one hand, in order to control the speed of the cutting;

mechanical stop to limit the penetration of said hollow-drill.

10. In a manually operated portable tool for cutting the armor strip of a BX cable; a clamp, having a cavity adapted to receive said cable; a tubular clamping screw, in threaded relation with said clamp, and adapted to secure said cable in said cavity; a hollow-drill, rotatably and slidably mounted within said clamping screw, and being so deeply recessed that it will not touch the cable when said cable is clamped by means of said screw; a crank, adapted to rotate and also axially press said hollow-drill, so as to effect and control the cutting by the use of one hand, in order to have the other hand free for the holding of said portable tool; a mechanical stop to limit the axial sliding of said hollow-drill.
